UNITED STATES PATENT OFFICE.

GEORGE A. FULLIPS, OF MILWAUKEE, WISCONSIN.

MACHINE FOR GRINDING VALVES.

Application filed May 5, 1921. Serial No. 467,066.

To all whom it may concern:

Be it known that I, GEORGE A. FULLIPS, a citizen of the United States, residing at Milwaukee, county of Milwaukee, and State 5 of Wisconsin, have invented new and useful Improvements in Machines for Grinding Valves, of which the following is a specification.

This invention relates to improvements 10 in machines for grinding valves.

The object of this invention is to provide improved mechanism adapted to produce the particular kind of motion best suited for the purpose. More particularly, 15 it is the object of this invention to provide a mechanism suitable for grinding any valve upon its seat by imparting to said valve a reciprocatory rotative motion and periodically raising it in opposition to a resilient 20 pressure tending to seat the valve so that the grinding compound which is being used will have an opportunity to flow again on to the valve seat from which it has been pressed in the grinding operation.

25 Further objects of this invention are to provide adequate means for supporting the member with the valve, whereby the valves in pipe fittings or in internal combustion engines may be handled equally well by this machine; to provide improved means for imparting the desired reciprocatory motion to the valve which is being ground; and to provide a mechanism adapted to be associated with others of the same kind to be 30 driven from a single source of power for the purpose of performing a great number of valve grinding operations at the same time.

In the drawings,

40 Figure 1 is a side elevation of a machine embodying this invention.

Figure 2 is a sectional view in elevation showing the valve operating shaft, remaining portions of the device being broken 45 away.

The frame of the machine comprises a support 1 mounted upon a base 2. The support may take the form of a box casting, as little metal being used therein as is possible, 50 consistent with suitable strength. In the bearing shown at 3, is journaled the shaft 4 which may be driven from a suitable source of power. A fly wheel 5 is preferably mounted thereon to make uniform the motion of the device. Adjacent to the fly

wheel is the sprocket wheel 6 provided for purposes hereinafter to be described.

The shaft 4 is provided with a crank 7 which operates the pitman 8 to impart to the rack 9 a vertical reciprocatory motion. 60 The rack 9 is preferably provided with a suitable sliding bearing upon the support 1. A pivotal connection 10 between the rack and the pitman 8 is provided for obvious reasons.

65 The rack 9 meshes with a gear wheel 11 mounted at the end of shaft 12, journaled in the uppermost portion of support 1, and provided adjacent to its other end with a beveled gear wheel 13.

70 A bracket arm 15 supported from the upper end of the box casting 1 provides a mounting for the shaft section 16 which is held in place by a collar 17. A beveled gear 18 carried by this short length of shaft meshes with the beveled gear 13 upon shaft 12. The hub of the beveled gear 18 is recessed at 19 to receive the clutch member 20, keyed to the shaft section 21. A bracket 22 carried by the frame of the machine 75 provides suitable bearings for this shaft. The projections 23 and 24, located respectively upon the bracket member 15 and the bracket member 22, provide a mounting for a slidable rod 25, having a handle 26, and a fork 27 engaged between the collars 28 and 29, whereby the engagement of clutch member 20 in the recess 19 may be effected to impart to shaft 21 the motion of shaft 16. At the lower end of shaft 21 is splined 80 an additional shaft section 30 so mounted in bracket 31 as to have a rotative and sliding bearing therein. A collar 32 upon this shaft serves as a seat for spring 33, the opposite end of which bears against the bracket 22. By means of this spring, the shaft section 30 is resiliently pressed downwardly. 85

In the lower end of the shaft section 30 a recess 35 is provided into which may be inserted a chuck 36 suitable for engagement with the particular valve to be ground. A transverse pin 37 may be inserted in a suitable opening to retain the chuck 36 in position.

100 The lever 40 pivoted at 41 within the box casting or support member 1 carries at its outer end a fork 42 adapted to engage the collar 32 for the purpose of raising the shaft section 30 against the resilient pressure of spring 33. It will be understood that shaft 105 110

30 is splined to shaft 21 so that the rotative movement of the latter shaft will be communicated to shaft 30 while permitting the vertical sliding movement of shaft 30. At 5 the rear of the machine frame 1 is journaled a transverse shaft 43 which carries a cam 44 and the sprocket wheel 45, the latter being connected by a chain 46 with the sprocket wheel 6 upon the main drive 10 shaft 4. The mechanism last described is so associated with the lever 40 that the rotation of shaft 43 and the cam 44 thereon will periodically actuate said lever to raise shaft section 30 in the manner already described.

A suitable table 50 is supported by a frame 51 having a sliding bearing upon the box casting 1. A rack 52 may be cast integral with the casting 1 or may be mounted 20 thereon. Suitable gear wheels 53 mounted upon a shaft 54 in the table supporting frame 51 are adapted to interact with the teeth of the rack 52 and may be actuated by any suitable means, such as a handle, 25 mounted upon the squared end of shaft 54, to raise or lower the table 50. The adjusting means thereby provided are adapted for quick but comparatively inaccurate operation of the table. If desired, the screw 55 30 may be threaded in the table and provided with a lock nut 56 to permit a more accurate adjustment of the auxiliary table 57, upon which may be mounted the device here represented by the valve casing shown at 58 35 which includes the seat 59 for the valve 60 which is to be ground. It will be understood that the auxiliary table 57 will be adapted to the particular work to be done and may be omitted altogether where valves 40 are to be ground into their seats upon a heavy casting, such as the cylinder of an internal combustion engine.

When in use, my improved valve grinding mechanism operates as follows.

45 Power being applied to the shaft 4, a reciprocatory motion will be imparted to the rack 9 through crank 7 and pitman 8. The rack 9 engaging with gear 11 will cause the shaft section 16 to rotate first in one direction and then in the other. Assuming that the clutch member 20 is engaged in the 50 recess 19, the reciprocatory rotative motion of shaft 16 will be communicated through said clutch, to shaft sections 21 and 30. It will be remembered that the shaft section 55 30 while adapted to be rotated by shaft 21 is also adapted to have a sliding motion relative to said shaft, but is normally pressed downwardly by the spring 33. With the 60 valve casing 58 mounted in the position shown in the drawing, the resilient downward pressure of spring 33 upon collar 32 will be communicated through shaft 30 and the chuck or tool 36 to the valve 60, thereby 65 pressing said valve tightly against its seat

while it is being rotated first in one direction and then in the other by the action of rack 9 upon gear wheel 11 and the mechanism above described. In the meantime, however, the sprocket wheel 45 is being 70 driven by chain 46 from the sprocket wheel 6 upon the power shaft 4 and the cam 44 is being operatively rotated thereby. The rotation of cam 44 actuates the lever 40 to lift periodically the shaft section 30, the 75 chuck 36 and the valve 60 allowing the grinding compound to penetrate anew to the valve seat 59. Obviously, this machine will operate most effectively to produce the proper reciprocating and lifting motion of 80 the valve to produce the best results.

It will be apparent to those skilled in the art that by using additional mechanism such, for example, as that shown in my copending application, Serial No. 469,606, filed May 14, 1921, to control the movement of the rack 9, the motion imparted to the valve may be varied if desired from the equal period reciprocatory motion which will result from the use of the mechanism here 90 shown and illustrated.

It will also be apparent to those skilled in the art that a large number of machines, each including a frame 1, may be set side by side. In this way valves could be ground simultaneously into a large number of internal combustion engine cylinders, the machines being so spaced that each machine would operate simultaneously upon the first valve in the cylinder block. By moving the 95 several cylinder blocks a short distance, the machines could be made to operate simultaneously upon the second valve in each cylinder block. The particular construction illustrated in this embodiment of my invention is particularly adapted for multiple use in the above described manner by reason of the fact that all of the mechanism is carried by a comparatively narrow frame. It is well known that some valves require a great deal 100 of grinding to adapt them to the seat with which they are to be associated, whereas other valves require very little.

I claim:

1. The combination with a frame, of a 115 work supporting table adjustable at the front thereof, a sectional shaft provided with means for supporting each section independently from the frame, a clutch disengageably connecting two sections of said 120 shaft, means for maintaining one of said sections in driving relation with a third section of the shaft, while permitting said third section a relative axial movement, and a chuck carried by said third section. 125

2. The combination with a machine frame and a power shaft journaled in the lower rear portion thereof, of a reciprocatory rack 130 slidably mounted adjacent the top of the frame, means for reciprocating said rack

from the power shaft, a horizontal shaft operatively associated with the rack adjacent the upper portion of the frame, three shaft sections in vertical axial alignment at the front of said frame, means for driving one of said sections from said horizontal shaft, means for disengageably connecting the driven section to a second section, a splined connection between the second section and the third section, whereby said third section is positively driven while free to move axially with respect to the second section, an adjustable table beneath said third section adapted to support a valve seat member and valve, resilient means for pressing said third section normally toward said adjustable

table, means operated from the power shaft for periodically relieving said pressure and a chuck carried by said third section.

3. In a device of the character described, 20 the combination with a power shaft; of a driven shaft comprising a section connected with said power shaft for receiving reciprocatory rotary motion therefrom and a second shaft axially spaced from, and aligned 25 with, said first section for movement axially relative thereto; a clutch engageable with the first section and having a splined connection with said second section, and a chuck carried by said second section.

GEO. A. FULLIPS.
